SWITCH CONTACT

Richard B. Hunter, Shorewood, Wis., assignor
to Cutler-Hammer, Inc., Milwaukee, Wis., a
corporation of Delaware

Application July 23, 1937, Serial No. 155,212

2 Claims. (Cl. 200—171)

This invention relates to switch contacts and more particularly to contacts of the type employed in connection with drum controllers, although it is to be understood that contacts of the character herein disclosed may be employed in other electrical devices.

An object of the invention is to provide an improved contact comprising a finger and a tip which may be easily and conveniently secured to the finger, in either one of two positions relatively to the latter, and which may be reversed after use thereof to afford maximum wear or life.

Another object is to provide a contact tip of the aforementioned character which is positively held against rotary movement with respect to the finger to which it is secured.

Another object is to provide a contact tip of the aforementioned character having an embedded securing element, wherein the embedded portion 20 of the securing element is sufficiently removed from the contact surface of the tip to provide an adequate amount of wear allowance.

Another object is to provide a contact tip in which the securing element is rigidly held and supported in a novel and effective manner.

Another object is to provide a readily removable and replaceable contact tip which is simple in construction and which can be produced economically.

Other objects and advantages of the invention will hereinafter appear.

Various forms of contact tips have heretofore been proposed, which individually possess certain advantages which are of value depending upon their application. Those contact tips which are adapted to be permanently secured to contact fingers, as by riveting, are satisfactory for use in drum controllers, for instance, which are employed in such relatively light service that wear and burning of the contact tips is negligible. However, controllers which are employed for relatively heavy duty service, such as requires frequent commutation of circuits carrying heavy currents, and in which high contact pressures are required, necessitate frequent replacement of the contact tips due to relatively rapid wear and burning thereof. It is obvious that a permanently secured contact tip is undesirable where frequent replacement is necessary, and in recognition of the need for an easily removable and attachable contact tip various forms thereof have heretofore been proposed.

In drum controllers the engagement of the contact tip with the cooperating contacts carried by the rotary drum is preferably effected with a

maximum width of the contacting areas, and accordingly a necessary feature of such a tip is to provide means whereby the same is non-rotatably held with respect to the contact finger. Such means, heretofore proposed, include such devices as an abutment formed at one end of the contact tip to cooperate with the outer end of the finger, the abutment however, preventing reversible attachment of the tip. Other tips are formed with recesses requiring a specially formed projection 10 on the contact finger, or a separate element carried by the finger and having a projection to cooperate with a recess or recesses in the tip.

The present invention provides the aforementioned feature of non-rotatable securing in a novel manner and other desirable features as set forth in the foregoing objects, and the advantages of such features will be apparent from the following description with reference to the single embodiment of the invention illustrated in the accompanying drawing; it being understood that the embodiment illustrated is susceptible of modification in respect of certain details of construction thereof without departing from the scope of the appended claims.

In the drawing, Figure 1 is a side elevational view, with parts thereof shown in vertical section, of a contact finger having secured thereto a form of contact tip embodying my invention;

Fig. 2 is a top plan view of the contact finger shown in Fig. 1;

Fig. 3 is a perspective view, in separated relation, of the improved contact tip shown in Fig. 1 and the outer end portion of the contact finger, showing a preferred form of the latter and indicating the manner of cooperation of the parts; and

Fig. 4 is a plan view of the contact tip.

Referring now more particularly to Fig. 1 of the drawing, the numeral 1 designates a segmental contact mounted on a rotary drum in a position to engage the contact tip 2 secured to the outer end portion of a contact finger 3. The rotary drums of drum controllers are usually provided with a plurality of segmental contacts, and contact 1 may be assumed to be one of a number of such contacts arranged on a drum to engage the contact tips on contact fingers, such as 3, which are fixed in side by side relationship to a suitable support, such as the substantially square, 50 insulated supporting rod 4. The rod 4 may be carried by the drum controller frame (not shown).

The supporting rod 4 is insulated by a tubular member 5 formed of suitable insulating material. 55

Contact finger 3 is secured to supporting rod 4 by clamping means comprising a clamping member 6 having arms 7 and 8 formed at a right-angle to each other to engage two sides of the rod 4. Arm 7 also forms a supporting base plate for the contact mechanism. Cooperating with clamping member 6 is a second clamping member 9 having arms 10 and 11 formed at a right-angle to each other to engage the other two sides of rod 4. The clamping members 6 and 9 are firmly held in clamping engagement with supporting rod 4 by bolts 12 and 13 and nuts 14.

Contact finger 3 is provided adjacent to the inner end thereof with an opening to freely receive the reduced portion 15 of bolt 12. A coiled compression spring 16 encircles portion 15 and is held under compression between the outer surface of contact finger 3 and the inner surface of a cup washer 17 which is retained on portion 15 by a cotter pin 18. The extreme inner end of contact finger 3 is bent downwardly and is formed in a manner to provide a bearing edge or surface 19 which seats within a saddle 20 or open bearing formed on the outer face of arm 7 of clamping member 6.

One end portion of a flexible conductor or pigtail 21 is secured to the inner end portion of contact finger 3, the other end of said conductor being secured on bolt 13 between nuts 14 and 22 together with a solder lug 23 of well known form.

Associated with contact finger 3 is a contact pressure adjusting device comprising a polygonal headed screw 24 the shank of which is threaded into a tapped opening in the contact finger and is adapted in the inactive position of said finger to engage the upwardly offset extension 25 of arm 7. Adjustment of screw 24 effects variation of the initial position of contact tip 2 and provides for correct inactive positioning of tip 2 as the latter wears down. A reflexed or substantially U-shaped spring element 26 is provided with an upwardly bent flat projection 27 which is adapted to yieldably engage any one of the flat sides of the head of screw 24 to effect retention of the latter in any adjusted position against displacement by vibration. One of the legs of spring element 26 engages the outer surface of contact finger 3 while the other leg engages the inner surface of the head of screw 24, said legs having aligned, relatively large openings to freely receive the shank of screw 24 and to provide a degree of longitudinal movement of spring element 26 to permit adjustment of screw 24.

When the rotary drum is of sufficiently large diameter to present the danger of arcing between the segmental contacts carried thereby and the metal clamping members of the contact mechanism supporting means, a shield 28 formed of suitable insulating material is preferably mounted on the extension 29 of clamping member 9 by a screw 30, as shown in Fig. 1.

The contact tip 2 comprises essentially a suitably shaped body of metal, preferably copper, having embedded therein the head 31 and a portion of the threaded shank of a securing element or stud 32, which is preferably made of steel. The stud and the contact tip are assembled in a well known manner;—the head 31 being inserted in a recess in the tip formed to receive it and the metal then pressed or flowed and shaped around it as by swaging or hot forging of the copper to positively lock the stud in position in the tip. The stud head 31 is illustrated in the drawing as being of flat circular form, the per-

iphery thereof being roughened, as by knurling, to form projections which interlock with the copper to prevent rotary displacement of the stud.

Contact tip 2 is formed with a flat upper surface 33 which is adapted to engage the flat lower surface of contact finger 3. The shank of stud 32 projects upwardly from the center of the surface 33 and is flanked on diametrically opposite sides thereof by an elongated, relatively low boss or projection 34 formed on said surface. Projection 34 is adapted to be accommodated within an elongated opening 35 formed in the forward end of contact finger 3, the walls of said opening closely engaging the periphery of said projection to positively and non-rotatably interlock the contact tip with said finger. By means of a nut 36 which is threaded on stud 32 and a lock washer 37 which is interposed between said nut and the upper surface of contact finger 3, the contact tip 2 is rigidly secured to said contact finger.

As best shown in Fig. 4 the width of the projection 34 corresponds substantially with the diameter of stud 32, this width being preferred to a lesser width to avoid specially forming the opening 35 to accommodate the shank of stud 32. Moreover, the width of projection 34 should be sufficient to present a relatively large peripheral wall surface for cooperative engagement with the walls of opening 35 and also to provide an adequate body of metal to prevent shearing of the projection by a wall of said opening when the nut 36 is turned to tighten the tip in position. On the other hand, a projection substantially larger than that shown is objectionable as it would require an opening 35 of such size as to materially weaken the contact finger.

It should be noted that the projection 34 is preferably arranged longitudinally with respect to the body of the contact tip 2, that is, in line with the direction of movement of the segmental contacts of the drum, and that the opening 35 is likewise preferably arranged longitudinally with respect to the contact finger 3. By this arrangement the shank of stud 32 is well supported by projection 34 in the direction of thrust, whether the drum is being rotated in one direction or the other.

The advantages of the aforescribed arrangement are particularly evident when it is pointed out that if the projection 34 were arranged transversely of the contact tip the desired support for the shank of stud 32 in the direction of thrust would not be provided unless the projection were made substantially wider; and further, if the opening 35 were arranged transversely with respect to contact finger 3, the latter would be materially weakened unless it in turn were made wider to accommodate an opening so arranged. However, it is usually desired to make drum controllers of as small size as is practically possible to conserve materials and reduce the cost thereof, and obviously if the contact fingers were required to be made wider than is necessary to serve their purpose, the center-to-center spacing of the fingers would be greater, thus materially increasing the size of the drum controller.

The character and arrangement of projection 34 serves a further and important purpose. In order to obtain the maximum amount of wear from the contact tip the stud head 31 should be embedded in the tip as far removed from the contact surface as possible. As best shown in Fig. 1 the projection 34 provides an added thickness of metal enabling the head 31 to be located

relatively close to the surface 33 of the contact tip 2 without danger of the stresses incurred during tightening of nut 32 or the stresses incident to operation of the drum resulting in displacement of the stud from its embedded position.

What I claim as new and desire to secure by Letters Patent is:

1. A contact tip comprising an integral body of relatively soft metal having surfaces for engagement with a cooperating contact and for engagement with a supporting finger, and having on the latter surface for interlock with such supporting finger a projection which is relatively low and of elongated form with parallel flat sides, and further comprising a securing member having a threaded shank terminating in a relatively thin wide head, such securing member being of relatively hard metal and having its head embedded in said body of relatively soft metal closely adjacent the finger engaging surface of said body for preservation of depth of the portion of said body subjected to wear and said projection on the finger engaging surface of said body being formed to overlie the head of said securing mem-

ber and closely to embrace the outwardly extending shank of said member, thus reenforcing said body of relatively soft metal at points subjected to strain by said securing member.

2. In a contact finger, in combination, a supporting member having an opening formed therein, said opening having at least one straight wall portion, a contact tip of relatively soft metal having a flat surface for engagement with said supporting member, the contact tip having a projection formed on said flat surface, said projection being adapted for interlocking non-rotatable and non-slidable engagement with the walls of said opening, and a securing element of a relatively harder metal having a head embedded in said tip closely adjacent to said flat surface to provide a wearing portion of maximum depth and having a threaded shank extending exteriorly of said tip substantially through the center of said projection, said element being adapted to assist in providing for securing of said tip to said supporting member.
